[57] CLAIM

The ornamental design for a keyless chuck, as shown and described.

DESCRIPTION

FIG. 1 is a front perspective view of a keyless chuck showing a first embodiment of my new design.

FIG. 2 is a left side elevational view of the first embodiment.

FIG. 3 is a front elevational view of the first embodiment.

FIG. 4 is a rear elevational view of the first embodiment.

FIG. 5 is a front perspective view of a keyless chuck showing a second embodiment of my new design.

FIG. 6 is a left side elevational view of the second embodiment.

FIG. 7 is a front elevational view of the second embodiment; and,

FIG. 8 is a rear elevational view of the second embodiment.
